UNITED STATES PATENT OFFICE

ADAM HENRY PRENZEL, OF HALIFAX, PENNSYLVANIA

LAUNDRY IRON

Application filed September 4, 1931. Serial No. 561,245.

This invention relates to improvements in laundry irons and it consists of the constructions, combinations and arrangements herein described and claimed.

5 An object of the invention is to provide a laundry iron, whether of the mechanically or manually operated type, the working face of which is provided with a peculiar type of interruptions consisting of a series of endless, 10 symmetrical depressions which have the particular function of providing spaces in which steam can gather.

A further object of the invention is to dispose the foregoing interruptions or depressions off-center in respect to the total area 15 of the smoothing plate, thereby locating the interruptions in advance of an uninterrupted portion of the working face, enabling a preliminary smoothing out of the wrinkles and 20 a secondary finishing of the cloth surface.

Other objects and advantages will appear in the following specification, reference being had to the accompanying drawings in which

25 Figure 1 is a side elevation of a familiar type of iron having an improved smoothing plate embodied therein,

Figure 2 is an inverted plan view of the iron particularly illustrating one type of interruptions in the working face or surface of 30 the smoothing plate,

Figure 3 is a cross section taken substantially on the line 3—3 of Figure 1,

Figure 4 is a detail inverted plan view of the iron illustrating how the rim groove may 35 be merged with one of the series of concentric depressions.

The conventional mode of smoothing articles of clothing is to apply a heated laundry iron under manual pressure. In order to cause the yielding of the wrinkles in a given area of cloth it is usually necessary to make repeated strokes in several directions before a satisfactory finish is secured. The operation of passing the iron back and forth as 40 well as laterally many times, is what makes ironing so arduous and in the majority of cases the most dreaded part of the work of the laundress.

As has been briefly brought out already, it 45 is the purpose of the instant invention to

provide a laundry iron which will enable the making of quicker work of smoothing out wrinkles in an article of clothing and thereby expediting the process of ironing. In the drawings the iron 1 (Fig. 1) may be regarded as of any known manual type, although this particular iron is of the electrically heated type in that the illustration shows one of a pair of electrical terminals 2 (Fig. 1) and a heating element 3 (Fig. 3).

It is to the smoothing plate 4 that the improvement has been made. Near the point 5 of the working face or surface of the smoothing plate there is an interruption or a series of interruptions 6. These depressions are endless and symmetrical in respect to a common center of symmetry thereby forming increasingly larger steam spaces. The depressions produce a plurality of individual smoothing elements 7, but it is the de- 70 pressions which have the following important action:—

When the hot iron is applied to a starched cloth, the moisture will be converted into steam. The steam enters the depressions or steam spaces 6 and in a degree carry the starch to the surface. The interruptions 6 are disposed off-center (Fig. 2) in respect to the working face of the smoothing plate 4, thereby leaving an interrupted portion 8 of 75 substantial area behind the interruptions, said area serving to smooth out the cloth and impart a polish to the raised starch.

The depressions 6 have another function 80 which operates equally as well when pressing either starched or unstarched cloth. In sprinkling clothing the water touches in spots and ordinarily is not spread over the cloth with uniformity. When the iron is applied, those portions which have been moistened 85 will produce steam that enters the depressions as already pointed out.

It then becomes the function of the depressions to carry moisture, so to speak, to other 90 and undampened parts of the cloth. The steam accumulates in the depressions as the iron goes along, and the accumulated steam is applied to the dry portions of the cloth, serving to moisten them sufficiently to result 95 100

in a perfectly clean and smooth pressing action.

The foregoing actions are augmented by a continuous groove 9 (Fig. 2) in the bottom of the plate 4 near its rim. This is a boundary groove, and it occurs in the bevelled portion of the plate 4. In other words, the plate 4 is bevelled on all sides as at 10. This bevel increases the area of the working face, and it is within the confines of this bevelled portion that the continuous groove 9 occurs. The effect of the groove 9 is much on the order of the individual grooving elements 7, especially near the point 5 of the iron, it being observed that in this arrangement there are at least two of the depressions 6 of the series of depressions which are of endless and of symmetrical form having a common center of symmetry.

When the iron is moved forwardly, the point 5 will not alone part the wrinkles but the point 11, brought into being by the presence of the groove 9, will do likewise. The showing of the groove 9 is partly for the purpose of making it clear that the purpose of the improvement is not necessarily achieved by concentric configurations such as the circular depressions 6 and resulting circular elements 7.

It is intended that the iron shall be made either with a combination of the depressions 6 and groove 9, or either of these singly. Moreover, it is not essential to adhere to the circular arrangement of interruptions 6 and elements 7. It is conceivable that depressions may be arranged in the working face of the plate 4 on a different order that will smooth out the cloth in advance of the uninterrupted portion 8.

As a further example, and particularly to show how the arrangement might be made otherwise than in Figure 2, it is to be noted in Figure 4 that the rim groove now denoted 12, but to be identified with the continuous groove 9 of Figure 2, merges with one of the series of interruptions or depressions 6 instead of passing clear of the outermost depression down to the point of the iron as in Figure 2. The arrangement in Figure 4 is not solely a matter of attractive design but also one of utility.

It is conceivable that in some instances the iron might work better with the area 13 (Fig. 4) adjacent to its point 5 left entirely clear and uninterrupted. In such event the arrangement in Figure 4 would be adopted or one similar to it. This arrangement naturally suggests that the rim groove 12 might be made to merge with the outermost depression 6 at points other than the tangential positions.

The thing to be chiefly borne in mind is that the depressions in the working face of the smoothing plate, which working face is perfectly plane, are endless in their configu-

ration so that regardless of what the specific design happens to be, there will be no point of egress for the entrapped steam at the edges of the smoothing plate. The main illustrations in Figures 2 and 4 show at least two of the depressions of annular form, but it is intended that the depressions shall be made according to other symmetrical arrangements having a common center of symmetry. From this it will be understood that the groove or grooves outside of such symmetrical depressions may follow the contour of the iron as in Figure 2 or it may communicate with an outside one of the symmetrical grooves and extend toward the rear of the iron, or on the same principle, said groove may communicate with the outside symmetrical groove and extend to the point of the iron.

I claim:

1. A laundry iron having a smoothing plate, the working face of said smoothing plate being perfectly plane and being provided with a series of endless, symmetrical depressions having a common center of symmetry, said depressions forming increasingly larger steam spaces.

2. A laundry iron having a smoothing plate, the working face of said smoothing plate being perfectly plane and being provided with a series of endless, annular, concentric depressions, said depressions forming increasingly larger steam spaces, said series of depression being disposed in off-center relationship to the working face leaving an uninterrupted portion of substantial area at one side of said series of depressions thereby serving to smooth out the cloth which was raised by the action of the steam discharging into said depressions.

3. A laundry iron having a smoothing plate, the working face of said smoothing plate being perfectly plane and being provided with a series of depressions surrounding one another at least two of which are endless, symmetrical, and have a common center of symmetry.

ADAM HENRY PRENZEL.
